UNITED STATES PATENT OFFICE.

JAMES G. WESTBROOK, OF OGDENSBURG, NEW YORK.

SPARK-PLUG.

1,127,330.

Specification of Letters Patent. Patented Feb. 2, 1915.

Application filed September 25, 1913. Serial No. 791,847.

To all whom it may concern:

Be it known that I, JAMES G. WESTBROOK, a citizen of the United States, residing at Ogdensburg, in the county of St. Lawrence and State of New York, have invented certain new and useful Improvements in Spark-Plugs; and I do hereby declare the following to be a full, clear, and exact description of the invention, such as will enable others skilled in the art to which it appertains to make and use the same.

This invention relates to spark plugs, and an object of the invention is to provide for heating, confining and compressing a small part of the charge in a radiator separated by a fine screen from the gas engine cylinder so that said charge may be exploded by the spark, whereupon a charge in the cylinder may be exploded by the smaller charge ignited by the spark plug.

Another object of the invention is to retain the heat of the explosion and prevent disastrous alternate heating and cooling of the breakable parts of the spark plug.

A further object of the invention is to provide means for safe-guarding the electrodes against carbonization, which is almost certain to take place in the best regulated of engines.

With these and other objects in view the invention comprises certain novel constructions, combinations and arrangements of parts as will be hereinafter more fully described and claimed.

The accompanying drawing shows a section through the plug and adjacent parts of the cylinder, but I wish it to be understood that any form of spark plug may be used, either high or low tension, without departing from the principle involved in the invention, although I have chosen to show a high tension spark plug in connection with the invention.

I am aware that it has been heretofore proposed to extend from the spark plug a tube which projects into the cylinder and has located therein the electrodes of the plug, but in almost every instance the electrodes are placed adjacent the lower end of the tube. I am also aware that it has been proposed to arrange a cap over the spark plug to house the electrodes, the cap being provided with perforations admitting the passage of gas to be ignited, but these perforations have been so large as to offer practically no resistance to the accumulation of

carbon upon the spark plug electrodes. The present invention aims to provide a tube, the upper end of which houses the electrodes while the lower end is closed with a fine 60 mesh screen.

Referring to the accompanying drawings it will be seen that the cylinder 1 is provided with the usual threaded hole 2 within which is located any approved form of spark plug 3, the lower end of which, as shown in the present instance, is threaded as at 4 and is cut off short enough to allow the upper threaded end 5 of tube 6 to be caught upon the threads of the hole 2. Tube 6, which 65 may be conoidal, cylindrical or of any other shape and of the proper size to house the desired amount of charge, has the lower end thereof closed with a screen 7 which may be a 50 mesh screen or finer. This screen may 70 be secured to the lower or inner end of the tube in any manner, but preferably it is enclosed within a ring 9 which is screwed onto external threads on the lower end of the tube 6.

80

It is desirable to have the electrodes 8 located at the upper or outer end of the tube, so that the spark will be effective in exploding the gas which is compressed within the tube rather than exploding directly the mixture within the cylinder outside the tube. It will be apparent that the tube forms a protection to the porcelain or other fragile parts of the plug, in that it prevents direct contact of said fragile parts with the 85 scavenging air, and that inasmuch as the greater part of the tube stands away from the wall of the cylinder the cooling of the cylinder by its jacket or otherwise will not reduce the temperature of the tube to any 90 appreciable extent, so that when the mixture is compressed that part which is forced into the tube will be heated to a temperature higher than that in the cylinder and the explosion for this reason facilitated. Hence 100 it may be said that the tube serves as a "radiator" which remains always sufficiently hot to warm that part of the charge within it and immediately next to the terminals of the plug. The screen 7 is for the 105 purpose of preventing floating particles of carbon which are formed at the time of explosion or immediately thereafter from passing into the tube and from being deposited upon the electrodes 8. The screen 110 is of extremely fine mesh, and I have found that if it is between 60 and 160 gage no oil

gathers on the electrodes, nor moisture which might serve to short-circuit the spark plug. Obviously, the charge within the tube is put under a pressure greater than the gas in the cylinder at the instant of explosion and the smaller confined charge thereupon ignites the charge in the cylinder. As the charge in the cylinder immediately adjacent the tube will be hotter than the charge remote from the tube, the flame of the exploding confined charge passing through the screen will ignite the charge in the cylinder.

I am aware that at the time of an explosion carbon forms in the cylinder in the form of an impalpable powder and that immediately thereafter these particles collect to form large particles which may become incandescent or be objectionable, and it is these larger particles which are to be excluded from contact with the electrodes by the screen.

What I claim is:

1. The combination with an internal combustion engine cylinder, and a spark plug in its head; of a hollow metallic element secured to the inner face of the head and surrounding the electrodes of the plug, the element having an opening into the interior of

the cylinder at a point remote from said electrodes, and a fine mesh screen across such opening.

2. The combination with an internal combustion engine cylinder having a threaded hole in its head, and a spark plug carried by said head with its electrodes projecting into said hole; of a tubular metallic element having its upper end screwed into said hole and inclosing the electrodes, and a fine mesh screen across said element at a point remote from the electrodes.

3. The combination with an internal combustion engine cylinder having a threaded hole in its head, and a spark plug screwed partway into said hole; of a tube screwed into the inner end of the hole against the inner end of the plug and inclosing the electrodes thereof, its body projecting for an appreciable distance into the cylinder, and a screen of extremely fine mesh across the inner end of the tube.

In testimony whereof I affix my signature in presence of two witnesses.

JAMES G. WESTBROOK.
